UNITED STATES PATENT OFFICE.

GEORGE M. HUBBARD, OF NEW HAVEN, CONNECTICUT, ASSIGNOR TO THE
W. & E. T. FITCII COMPANY, OF SAME PLACE.

DESIGN FOR A LEVER FOR SASH-FASTENERS.

SPECIFICATION forming part of Design No. 27,572, dated August 24, 1897.

Application filed July 6, 1897. Serial No. 643,667. Term of patent 14 years.

To all whom it may concern:

Be it known that I, GEORGE M. HUBBARD, of New Haven, in the county of New Haven and State of Connecticut, have invented a new Design for Levers for Sash-Fasteners; and I do hereby declare the following, when taken in connection with the accompanying drawings and the letters of reference marked thereon, to be a full, clear, and exact description of the same, and which said drawings constitute part of this specification, and represent, in—

Figure 1, a perspective view of a lever embodying my design; Fig. 2, an end view of the same; Fig. 3, a rear view; Fig. 4, a section on line *a b* of Fig. 1.

This invention relates to a design for levers for sash-fasteners; and it consists in the configuration, as hereinafter described, and shown in the accompanying illustration.

The lever consists of a substantially semi-circular plate, the under face A of which is flat, and the upper surface having a finger-piece B and a winding inwardly-beveled surface C, which tapers from the finger-piece down to the opposite edge, forming in transverse section the segment of a circle. 20 25

I claim—

The design for levers for sash-fasteners as herein shown and described.

In testimony whereof I have signed this 30 specification in the presence of two subscribing witnesses.

GEORGE M. HUBBARD.
